CARRIER CARTON WITH HOLLOW, RECESSED CENTER RETAINING MEMBER FOR CYLINDRICAL OBJECTS

Francis Arndt Chidsey, Jr., Devon, Pa., assignor to Container Corporation of America, Chicago, Ill., a corporation of Delaware

Filed Dec. 13, 1963, Ser. No. 330,420
8 Claims. (Cl. 220—115)

This invention relates to multi-pack cartons formed of paperboard, and more particularly to an open-end, sleeve-type carton for holding two parallel rows of generally cylindrical objects, such as cans or bottles, arranged in side-by-side relation.

The invention comprehends an improved center retaining member on one wall of the carton adapted to restrict the movement of the containers relative to the carton wall.

An object of the invention is the provision of a tubular carton, formed from a unitary blank of foldable paperboard, having a hollow retaining member formed integrally with one wall of the carton and extending longitudinally of the carton between a pair of rows of packaged articles.

A more specific object of the invention is to provide, in a carton of the type described, a hollow, integral, center retaining member formed on one wall of the carton and having alternately spaced article engaging and article non-engaging portions, the former of which are provided with a longitudinally extending contour line cut through at least a portion of the retaining member to permit the sides of the retaining member to deflect inwardly and assume the general contour of the articles between which the center retaining member is compressed.

These and other objects of the invention will be apparent from an examination of the following description and drawings, wherein:

FIGURE 1 is a perspective view of a carrier carton having a center retaining member embodying features of the invention;

FIGURE 2 is a fragmentary, longitudinal, vertical section taken on line 2—2 of FIGURE 3;

FIGURE 3 is a fragmentary, longitudinal, horizontal section taken on line 3—3 of FIGURE 2;

FIGURE 4 is vertical section taken on line 4—4 of FIGURE 2;

FIGURE 5 is a perspective view of an article engaging section of the can retaining member illustrated in the other views;

FIGURE 6 is a plan view of a blank from which the carrier carton of the other views may be formed;

FIGURE 7 is an enlarged view of a portion of the blank illustrated in FIGURE 6, showing that part of the structure which is also illustrated in FIGURE 5;

FIGURES 8, 9, 10, 11, and 12 are similar to views illustrated in FIGURES 2, 3, 4, 5, and 7, respectively, but illustrating a modified form of the invention; and

FIGURES 13 and 14 are fragmentary perspective views similar to FIGURE 1 but illustrating yet other forms of the invention.

It will be understood that, for purposes of clarity, certain elements have been intentionally omitted from certain views where they are believed to be illustrated to better advantage in other views.

Referring now to the drawings for a better understanding of the invention and particularly to FIGURES 1 and 2, it will be seen that the carrier carton illustrated in FIGURE 1 may be formed from a single blank B of foldable paperboard illustrated in FIGURE 6 of the drawings.

The carton is of the sleeve-type and includes parallel spaced top and bottom walls 10 and 12, respectively,

2

which are interconnected by a pair of spaced parallel side walls 14 to define a tubular structure, open at the ends, adapted to hold in side-by-side relation two parallel rows of cylindrical articles such as cans A having at one or both ends thereof peripheral flanges or chimes C projecting outwardly therefrom.

Still referring to FIGURE 1 it will be seen that one wall of the carton, in the case of the carton illustrated in the drawing is the top wall 10, is formed from a pair of generally co-planar outer and inner top wall panels 16 and 18, respectively, which are hingedly connected at their outboard edges to the upper edges of related side walls 14 and which have their inner portions disposed in overlapped relation and adhesively interconnected as at 19.

15 Referring now to FIGURES 1 through 4 it will be seen that top wall 10 is provided with inwardly projecting center retaining member 20 which is formed from the inner top wall panel 18 and which may extend longitudinally for the entire length of the carton.

20 The center retaining member is preferably rectangular or trapezoidal in cross-section and may be formed by a series of folds in the inboard portion of inner top wall panel 18 which provide an inner panel 22, disposed parallel to and spaced inwardly from top wall 10, and a pair 25 of side panels 24 which, together with the related portion of outer top wall panel 16, form a four sided, hollow structure.

As best seen in FIGURES 2 and 3, the longitudinal center retaining member is divided into a plurality of 30 alternately spaced article engaging sections and article non-engaging sections 26 and 28, respectively, one of the article engaging sections and parts of the adjacent non-engaging sections being illustrated more clearly in FIGURE 5.

35 Still referring to FIGURE 5, it will be seen that article engaging section inner panel 22 is provided with a longitudinally extending contour line 30 cut at least partially through the inner panel and having at the ends thereof pairs of similar, relatively short contour lines 32 which cooperate with each other and with the fold lines connecting the inner panel of the retaining member to the side panels to permit the areas of the side panels 24 adjacent the contour lines to be depressed or deflected inwardly when compressed between a pair of cans of opposed rows.

40 As these surfaces of the members side panels assume the general contour of the articles, they act to prevent the movement of the articles longitudinally of the carton. Also, to prevent the movement of the articles vertically of the carton the side panels 24 of the retaining member, 45 in the article engaging sections, may be provided with longitudinally extending openings 36 disposed immediately adjacent top wall 10 and adapted to receive peripheral portions of the can chimes C.

50 Thus, it will be seen that by providing the longitudinal center retaining member with the spaced contour lines it is possible to deflect the sides of the retaining member inwardly at each pair of cans to form pockets which receive the cans and prevent their movement longitudinally of the carton, and at the same time by providing the openings 36 the vertical movement of the cans is limited or prevented.

55 In the event the carton is used to package cans having chimes at both ends thereof the carton may be provided with a plurality of longitudinally spaced chime receiving openings 40 located at the corners between side walls 14 and bottom wall 12 of the carton.

60 In order to prevent the chimes of opposing pairs of cans from riding over each other both bottom and top walls 12 and 10 of the carton may be provided with inwardly projecting partition flaps 42 and 44, respectively, which are cut from the respective walls and project inwardly at right

angles thereto between the rows of cans. In the case of the top wall partition flaps 44, the flaps actually project into the hollow retaining member.

In order to facilitate lifting and carrying of the carton, top wall 10 may be provided with a pair of conventional finger grip openings 46.

Turning now to FIGURES 8 through 12 of the drawings wherein is illustrated a modified form of the invention it will be seen that the carton construction is similar to that of the other views with the exception of the structural arrangement of the article engaging sections of the center retaining member.

As best seen in FIGURE 11 the retaining member is provided with a pair of contour lines 30a which are cut completely through the inner panel 22 to permit the related portions of the side panels 24 to deflect inwardly and form pockets for receiving portions of the articles between which the retaining member is compressed to limit or prevent movement of the packaged articles.

Turning now to FIGURES 13 and 14 it will be seen that various ways are shown for obtaining the material for forming the center retaining member.

In the embodiment illustrated in FIGURE 13 the center retaining member is formed entirely from stock taken from the inner top wall panel 18a which has been provided with a plurality of parallel crease lines to form retaining member inner panel 22a side panels 24a with the outer surface of the end portion of panel 18a being adhesively secured to the inner surface of the related top wall outer panel 16a.

In FIGURE 14 a similar arrangement is used to form the center retaining member out of one of the top wall panel sections. However, in the case of FIGURE 14 the outer top wall panel 16b has an end portion 17 extending inwardly at right angles thereto and secured to the side panel 24b of the center retaining member. In each of these arrangements the formation of the article engaging sections of the center retaining member is formed in either of the two previous manners.

I claim:

1. An open end, generally rectangular, sleeve-type carrier carton, formed from a unitary blank of foldable paperboard, for holding two parallel rows of generally cylindrical articles in side-by-side relation, comprising:
  - (a) opposing pairs of spaced walls hingedly interconnected to define a tubular structure enclosing the ends and sides of the articles;
  - (b) one of the walls enclosing the ends of the articles being formed of a pair of generally co-planar panels;
  - (c) said panels having corresponding outboard parts hingedly connected to respective adjacent walls of the carton;
  - (d) said panels having inboard parts interconnected and arranged to form a longitudinally disposed center retaining member extending inwardly into the carton, throughout the entire length of the carton, between the two rows of articles;
  - (e) said retaining member having an inner portion and a pair of side portions which form, with an adjacent portion of said one wall, a hollow structure having article engaging and article non-engaging sections alternately spaced from each other longitudinally of the member;
  - (f) the non-engaging sections of said retaining member being substantially trapezoidal in cross-section;
  - (g) the engaging sections of said retaining member each having at least one longitudinally extending contour line cut at least partially through said inner portion to accommodate the inward deflection of the side portions of the engaging section when they are compressed between a pair of articles of opposed rows, so that the side portions assume the general contour of said articles;
  - (h) said engaging sections having in each side portion a longitudinally extending opening disposed adjacent

4
said one wall for receiving a radially outwardly projecting part of the related article.

2. An open end, generally rectangular, sleeve-type carrier carton, formed from a unitary blank of foldable paperboard, for holding two parallel rows of generally cylindrical articles in side-by-side relation, comprising:

- (a) opposing pairs of spaced walls hingedly interconnected to define a tubular structure enclosing the ends and sides of the articles;
- (b) one of the walls enclosing the ends of the articles being formed of a pair of generally co-planar panels;
- (c) said panels having corresponding outboard parts hingedly connected to respective adjacent walls of the carton;
- (d) said panels having inboard parts interconnected and arranged to form a longitudinally disposed center retaining member extending inwardly into the carton, throughout the entire length of the carton, between the two rows of articles;
- (e) said retaining member having an inner portion and a pair of side portions which form, with an adjacent portion of said one wall, a hollow structure having article engaging and article non-engaging sections alternately spaced from each other longitudinally of the member;
- (f) the engaging sections of said retaining member each having at least one longitudinally extending contour line cut at least partially through said inner portion to accommodate the inward deflection of the side portions of the engaging section when they are compressed between a pair of articles of opposed rows, so that the side portions assume the general contour of said articles;
- (g) said engaging sections having in each side portion a longitudinally extending opening disposed adjacent

3. An open end, generally rectangular, sleeve-type carrier carton, formed from a unitary blank of foldable paperboard, for holding two parallel rows of generally cylindrical articles in side-by-side relation, comprising:

- (a) opposing pairs of spaced walls hingedly interconnected to define a tubular structure enclosing the ends and sides of the articles;
- (b) one of the walls enclosing the ends of the articles being formed of a pair of generally co-planar panels;
- (c) said panels having corresponding outboard parts hingedly connected to respective adjacent walls of the carton;
- (d) said panels having inboard parts interconnected and arranged to form a longitudinally disposed center retaining member extending inwardly into the carton, throughout the entire length of the carton, between the two rows of articles;
- (e) said retaining member having an inner portion and a pair of side portions which form, with an adjacent portion of said one wall, a hollow structure having article engaging and article non-engaging sections alternately spaced from each other longitudinally of the member;
- (f) the engaging sections of said retaining member each having at least one longitudinally extending contour line cut at least partially through said inner portion to accommodate the inward deflection of the side portions of the engaging section when they are compressed between a pair of articles of opposed rows, so that the side portions assume the general contour of said articles.

4. A generally rectangular, sleeve-type carrier carton, formed from a unitary blank of foldable paperboard, for holding two parallel rows of generally cylindrical articles in side-by-side relation, comprising:

- (a) opposing pairs of spaced walls hingedly interconnected to define a tubular structure enclosing the ends and sides of the articles;

- (b) one of the walls enclosing the ends of the articles being formed of a pair of generally co-planar panels;
- (c) said panels having corresponding outboard parts hingedly connected to respective adjacent walls of the carton;
- (d) said panels having inboard parts interconnected and arranged to form a longitudinally disposed center retaining member extending inwardly into the carton, throughout the entire length of the carton, between the two rows of articles;
- (e) said retaining member comprising a hollow structure having article engaging and article non-engaging sections alternately spaced from each other longitudinally of the member;
- (f) the engaging sections of said retaining member each having at least one longitudinally extending contour line cut at least partially therethrough to accommodate the inward deflection of the side portions of the engaging section when they are compressed between a pair of articles of opposed rows, so that the side portions assume the general contour of said articles.

5. A generally rectangular, sleeve-type carrier carton, formed from a unitary blank of foldable paperboard, for holding two parallel rows of generally cylindrical articles in side-by-side relation, comprising:

- (a) opposing pairs of spaced walls hingedly interconnected to define a tubular structure enclosing the ends and sides of the articles;
- (b) one of the walls enclosing the ends of the articles being formed of a pair of generally co-planar panels;
- (c) said panels having corresponding outboard parts

5
10

- hingedly connected to respective adjacent walls of the carton;
- (d) said panels having inboard parts interconnected and arranged to form at least one hollow center retaining member extending inwardly into the carton between a pair of articles of opposed rows;
- (e) said retaining member having at least one longitudinally extending contour line cut at least partially therethrough to accommodate the inward deflection of the side portions of the member when they are compressed between said pair of articles, so that the side portions assume the general contour of said articles.

15. A carton according to claim 5, wherein said retaining member is formed entirely from one of the panels of said one wall.

7. A carton according to claim 5, wherein said retaining member is formed from portions of both of the panels of said one wall.

8. A carton according to claim 5, and including a partition flap cut from one of the panels of said one wall and extending normal to said one wall into the interior of said retaining member between said pair of articles.
